DESIGN FOR A TIRE CASING

Emanuel Rosenfeld, Philadelphia, Pa.

Application November 21, 1934, Serial No. 54,106

Term of patent 14 years

To all whom it may concern:

Be it known that I, Emanuel Rosenfeld, a citizen of the United States, residing at Philadelphia, in the county of Philadelphia and State of Pennsylvania, have invented a new, original, and ornamental Design for a Tire Casing, of which the following is a specification, reference being had to the accompanying drawing, forming part thereof.

Figure 1 is a fragmentary side elevational view of a tire casing, showing my new design.

Figure 2 is a top plan view of Figure 1 illus-

trating in particular the traction elements of the tread.

Figure 3 is a transverse vertical sectional view through the tire casing, the section being taken on the irregular line 3—3 of Figure 2.

Figure 4 is an enlarged fragmentary detail section showing the side wall contour.

I claim:

The ornamental design for a tire casing as shown.

EMANUEL ROSENFIELD
